UNITED STATES PATENT OFFICE.

JESSE ALEXANDER, OF BROOKLYN, NEW YORK, ASSIGNOR OF ONE-HALF TO GEORGE W. POTTER, OF BROOKLYN, NEW YORK

TYPE-BAR-OPERATING MECHANISM.

1,150,801.

Specification of Letters Patent. Patented Aug. 17, 1915.

Application filed November 13, 1914. Serial No. 871,879.

To all whom it may concern:

Be it known that I, JESSE ALEXANDER, a citizen of the United States of America, and residing at New York, borough of Brooklyn, in the county of Kings and State of New York, have invented new and useful Improvements in Type-Bar-Operating Mechanism, of which the following is a specification.

10 One object of my invention is to provide a key and type bar action of simple construction and having a light touch and a quick action. In the accomplishment of this object I operate the type bars from the key levers by means of links which are pivoted to the key levers at their lower ends and have both a lost-motion and a positive driving engagement with the type bars at their upper ends.

15 Another object is to render possible the bodily adjustment or removal of all the type bars in respect to the body of the machine. This object I have accomplished by connecting the type bars with the key levers in such a way that they may be readily detached therefrom and by supporting the type bars in a segment which is capable of being adjusted in respect to the frame or wholly detached therefrom.

20 A further object is to make possible the simultaneous adjustment of the tension of all the key levers. I accordingly provide a spring comb having spring fingers bearing on the key levers and mount this comb in a supporting bar which can be adjusted toward and away from the key levers for the purpose of increasing or decreasing the tension on all the keys at once.

25 Other features of the invention will appear as the specification proceeds.

In the drawings accompanying this specification I have illustrated in concrete form, a practical embodiment of the invention but I would have it understood that various 30 changes and modifications may be made without departing from the true scope of the invention.

Figure 1, is a vertical sectional view of a typewriter embodying the invention with the parts shown in their normal position of rest. Fig. 2, is a similar view with the parts in the printing position. Fig. 3, is a combined top plan and side view of one of the type bars. Fig. 4, is a combined edge and 35 side view of one of the intermediate links.

Fig. 5, is a broken detail view illustrating one method of adjustably and detachably supporting the type bar segment. Fig. 6, is a broken detail view of the key tensioning means showing a form of adjustable and 60 detachable support therefor, this view being taken looking from the front toward the rear of the machine. Fig. 7, is a plan view of the comb plate and its supporting bar. Fig. 8, is a detail view of one of the spring 65 fingers, illustrating its engagement with one of the type bars.

In the illustration, the frame, which may be of any approved construction, is designated 11. The key levers 12, are suitably 70 pivoted in the frame, as by being engaged on a pivot pin or rod 13. The type bars 15, are pivoted at 16 in a type bar segment 17. This type bar segment is, in the present illustration, adjustably and detachably 75 mounted in the frame by means of screws 18 passed through slots 19 in the segment into engagement with screw seats provided in the segment plate 20 at the back thereof. This segment plate may be secured direct 80 to the side plates 11^a of the frame, substantially as indicated in Fig. 5.

The driving connections from the key levers to the type bars are in the form of intermediate links 22 pivoted at their lower 85 ends at 23 to the key levers and having at their upper ends a positive driving connection with the type bars for starting the printing stroke and a lost-motion connection for continuing the printing stroke. In the 90 illustration the initial positive driving engagement is effected by providing the type bar with a rearwardly extending arm 24 terminating in an angularly extending lug 25 and providing the link with a rearwardly extending arm or hook 26 at its 95 upper end overlying the lug on the type bar arm. The lost-motion connection illustrated is of the pin and slot type, the pin 27 being carried by the type bar arm and the slot 28 100 being formed in the upper end of the link. The lost-motion connection, it will be noted, is located closer to the pivotal center than the positive driving connection and the leverage therefore is greatest at the start.

105 From the foregoing it will be clear that upon depression of the key lever, the intermediate link will be drawn down and the rearwardly extending arm on the upper end of said link engaging with the lug on the 110

rear end of the type bar arm will start the type bar on its printing stroke, utilizing the full leverage of the type bar arm. The type bar arm is thus started with a quick 5 movement and by reason of the direct pull on the arm and the considerable leverage exerted only a light touch is necessary. After the type bar has been thus started on, 10 its printing stroke, the lost-motion connection becomes effective and serves to carry the type bar the balance of the stroke to the full printing position. At the end of the printing stroke the lug 25 on the type bar arm may be caused to engage the rear 15 edge of the intermediate link as indicated in Fig. 2 to start the type bar on its return stroke.

To permit of the removal of the segment and type bars the connections between the 20 type bars and key levers are preferably made readily detachable. This is accomplished in the illustration by providing the intermediate links with keyhole slots 30 whose larger ends are of sufficient size to 25 take the heads of the headed pivot studs 23 on the key levers. Disengagement is effected by depressing a key lever and then holding the type bar in elevated position while releasing pressure on the key. The 30 key spring then exerts its force to throw the lever upward and carry the pivot pin 23 up into the enlarged upper end of the slot, whereupon by a slight lateral movement of the lever or link, the pin may be disengaged 35 from its slot. Usually the slot is formed with a shoulder 31, adjacent its lower end which normally overlies the pivot pin so that in the position indicated in Fig. 2, at commencement of the return stroke, a 40 straight upward push will be exerted on the intermediate lever, which will act to throw the type bar back to its position of rest. In disconnecting the links from the key levers as described above, it may be 45 necessary first to shift the links rearwardly slightly to effect a disengagement of the shoulders from the pivot pins.

The key levers are yieldingly supported by the spring fingers 33 of a comb plate 34, 50 which extends transversely beneath the key levers and with the fingers 33 thereof arched upward into engagement with the lower edges of the levers. These fingers may be grooved at their ends as indicated at 55 Fig. 8, to fit the edges of the levers. The spring comb is carried by a suitable supporting bar 36, as by being engaged in a grooveway 37 therein and this bar is shown as engaged at its ends on the screw studs 60 38 and held in adjusted position on said studs by the check nuts 39. It will be evident that by the raising or lowering of the spring comb the tension on all the key levers may be simultaneously adjusted.

65 The invention is of marked simplicity,

the parts few and light in weight and the action is a quick one and light of touch. The tension of the key levers and hence the force required to operate the machine may be readily determined by shifting the spring 70 comb in respect to the key levers and by the one and the same adjustment the tension of all the keys is fixed. The bodily removability of the type bars is of especial advantage in that it permits of the ready removal and substitution of different kinds 75 of type in the same machine.

What I claim is:—

1. In a typewriting machine, a key lever, a pivoted type bar provided with an arm 80 extending rearwardly from the center of pivotal support, a link pivoted to the key lever and having a positive driving engagement with the type bar arm at a point remote from the pivotal center at the commencement of the printing stroke thereof and a lost-motion connection between said link and type bar arm located at a point closer to the pivotal center than the aforesaid positive driving connection. 85

2. In a typewriting machine, a key lever, a pivoted type bar provided with an arm extending rearwardly from the center of pivotal support, a link pivoted to the key lever at its lower end, a lost-motion connection between the upper end of the link and the type bar arm and an arm on the upper end of the said link extending rearwardly from the lost-motion connection and engaging the type bar arm at a point in rear of 90 said lost-motion connection. 95

3. In a typewriting machine, a key lever, a pivoted type bar provided with a rearwardly extending arm having an angularly extending lug at the end thereof, a link pivoted to the key lever at its lower end, a lost-motion connection between the upper end of said link and the type bar arm and an arm on the upper end of the link extending rearwardly from the lost-motion connection into 100 position above the angularly extending lug on the type bar arm to thereby provide a positive driving connection with the type bar at the commencement of the printing stroke. 110

4. In a typewriting machine, a pivoted type bar, provided with an arm extending rearwardly from the center of pivotal support thereof, a pivoted key lever, an intermediate link pivoted to the key lever at one end and engaging the type bar arm at its opposite end at a point remote from the pivotal center at commencement of the printing stroke, a lost-motion connection between the link and type bar arm located at a point less 120 remote from the pivotal center and arranged to become effective after commencement of the printing stroke and the said type bar arm engaging the rear edge of the intermediate link at the end of the printing stroke. 125

to thereby start the type bar on its return stroke.

5. In a typewriting machine, a pivoted key lever, a pivoted type bar, an intermediate link pivoted to the type bar at its upper end and provided with a keyhole slot in its lower end, said slot being formed with a shoulder adjacent to and above the lower end thereof and a headed pivot stud on the 10 key lever engaged normally beneath the shoulder of the keyhole slot.

6. In a typewriting machine, a supporting frame, pivoted key levers mounted in the

frame, pivoted type bars, connections from the key levers to the type bars, a type bar 15 segment supporting the type bars and provided with slots in the ends thereof, and securing screws passed through said slots into the supporting frame whereby said segment carrying with it the type bars may be adjusted and secured in adjusted position on the frame.

JESSE ALEXANDER.
